[57] ABSTRACT

A control handle for a surgical aspirator comprising a rigid tubular body having an axial passage. An external circumferential groove is formed in the body with a plurality of radial holes connecting the bottom of the groove with the passage. An elastic ring seats in the groove and is movable for controlling the magnitude of suction in said passage by adjustably clearing the holes.

SUCTION CONTROL HANDLE FOR SURGICAL ASPIRATOR

This invention relates to surgical aspirators and more particularly concerns an improved control handle for a surgical aspirator.

Suction catheters, aspirators and evacuators have been used heretofore for aspiration of mucus from nose, mouth, pharynx, trachea and bronchi of patients, for evacuating the contents of uteri and other body organs. The precise, instant control of suction applied to a body organ has always presented considerable difficulty. Usually suction has been controlled by placing a thumb or forefinger over an aperture near the proximal end of a catheter or evacuator. This method of control has proven unsatisfactory because the doctor or nurse handling the instrument must often have both hands free to manipulate the instrument while the suction remains on. However, when the hand closing the suction control aperture is removed, the suction undesirably drops by venting to outside atmosphere. Various expedients have been proposed and tried in the past for controllably shutting off the apertures in instruments used for aspirations, but they have not gained general professional acceptance because of many undesirable features.

The present invention is directed at overcoming the drawbacks and disadvantages of prior suction control devices of surgical aspirators and at providing a new, improved, simple and safe control handle for a surgical aspirator.

According to the invention a control handle for a surgical aspirator is provided which serves as a coupling device between a suction pump and the instrument which is inserted into the patient's body for application of suction thereto. The handle is tubular in form and is provided with an external circumferential groove at the inside of which are circumferentially spaced radial holes. An elastic rubber ring movably seats on curved shoulders formed at outer edges of the groove. This ring normally seals off the interior of the control handle from outside atmosphere. However, the user of the instrument, by application of thumb, forefinger or any one or more fingers may displace the elastic ring partially or entirely and can thus effect control of suction applied to the patient. The control handle includes provisions for a fitting by means of which a suction hose from a suction pump may be quickly and easily connected to the control handle.

It is therefore a principal object of the present invention to provide a control handle for a surgical aspirator, wherein an elastic ring is movably seated in an external circumferential groove having spaced radial holes.

A further object of the present invention is to provide a control handle of the type described having a rigid tubular body which is dimensionally stable, resistant to chemical decomposition, light in weight, and relatively inexpensive to manufacture.

These and other objects and many of the attendant advantages of this invention will be readily appreciated as the same becomes better understood by reference to the following detailed description when considered in connection with the accompanying drawings in which:

FIG. 1 is a side view of a control handle embodying the invention, shown held in one hand and manipulated by fingers to control the applied suction;

FIG. 2 is an enlarged side view of the control handle shown with parts of a suction hose and evacuating instrument connected thereto;

FIG. 3 is a further enlarged longitudinal sectional view taken along line 3-3 of FIG. 2;

FIG. 4 is a longitudinal sectional view of the handle per se with the control ring mounted thereon;

FIG. 5 is a transverse sectional view taken along line 5-5 of FIG. 3;

FIG. 6 is a transverse sectional view taken along line 6-6 of FIG. 4;

FIG. 7 is a further enlarged fragmentary sectional view of a portion of FIG. 3 showing one way the control ring of the device may be manipulated and set; and

FIG. 8 is an exploded perspective view of parts of the device on a reduced scale.

Referring, now to the drawings wherein like reference characters designate like or corresponding parts throughout, there is illustrated a control handle generally designated as reference numeral 10 for a surgical aspirator assembly. The handle 10 as most clearly shown in FIG. 3 has a tubular body 11 with one cup-like end portion 12 being cylindrical with a cylindrical passage portion 15. The body portion 12 has a bead 14 on its free end and is adapted to receive a cylindrical end portion 16 of a nipple 20 which serves to couple a hose or pipe 22 to the handle 10. The other end of the hose 22 terminates at a suction pump (not shown).

The tubular body 11 has a cylindrical passage portion 25 which is concentric with the passage 15 and communicates with an outwardly flaring conical passage 26. A portion 13 of the exterior of the tubular body 11 flares outwardly and at its cross section of maximum diameter the tubular body 11 is formed with an external circumferential groove 30. A plurality of circumferentially spaced radial holes 32 are formed in the inside wall 26a of the groove 30 to provide lateral communication between the interior and exterior of the tubular body 11. The outer rims 33 of the opposing edges of the groove 30 are concave as clearly shown in FIGS. 3, 4 and 7. These concave rims are annular and extend circumferentially all around body 11 as best illustrated in FIGS. 6, 7 and 8. End portion 35 of body 11 is tapered from groove 30 to the free end of body 11.

An elastic ring 40 made of natural or artificial rubber seats snugly on the seats or shoulders defined by the concave rims 33 to seal the groove 30 and the holes 32.

This ring can be rolled or moved axially of the tubular body 11 to clear the entire groove as shown in FIGS. 1, 4, and 6. Alternatively it may be stretched and moved obliquely as shown in FIG. 7 so that part of the ring 40 remains engaged in the groove 30 and other parts are

partially or wholly clear of the holes 32. Displacement of the ring 40 is performed by any one or more fingers F of hand H which holds the handle 10 as shown in FIG. 1. The handle may be held in the right or left hand with equal facility.

The conical passage portion 26 of the body 11 may receive a tapered end 42 of a catheter tube, uterine evacuator tip or other instrument 43 (FIG. 8). The end 42 of the instrument 43 will be snugly engaged but may easily be pulled axially out of the body 11.

The nipple 20 which fits into the end portion 12 of the body 11 has a circumferential groove 45 in which a compressible sealing ring 46 may be seated. The ring

46 normally extends radially outwardly of the cylindrical portion 16 of the nipple 20 as shown in FIG. 8. However when the nipple 20 is fully inserted into the end portion 12 of the body 11 as shown in FIG. 3 the ring 46 is compressed and hermetically seals the space 5 between the nipple 20 and the wall of body portion 12. This ring also serves as a friction gripping member to hold the nipple 20 in the tubular body 11. A pair of spaced conical portions 48 are formed at the distal end 10 of the nipple 20. These serve as friction gripping elements to engage the proximal end of hose 22. The free end of the hose 22 will fit into an annular enlargement 50 of passage portion 15.

The handle 10 is preferably made of rigid, transparent plastic material which may be sterilized for repeated use. Other suitable materials are acetate copolymers, polystyrene, aluminum etc. These materials are dimensionally stable, light in weight, relatively inexpensive, and easy to manufacture. Fitting 20 is 15 preferably made of nylon or other tough, durable material which may be sterilized for repeated use. Both handle 10 and fitting 20 are resistant to chemical decomposition. They resist acid, alkaline, and other chemical agents. The nylon fitting has a smooth self-lubricated surface to facilitate attachment of the hose 22.

The handle 10 may be held in the hand conveniently and comfortably. Ring 40 is easily manipulated for suction control. It may be left in place as shown in the drawings partially or fully closing the holes 34 or fully clear of the holes, to leave the hand H free for handling of the patient or instrument 43, or for performing other tasks while the suction applied remains constant depending on the setting of the ring 40. The ring 40 may 35 be replaced after each use if desired or it may be sterilized for repeated use. All parts of the assembly may be quickly disassembled for cleaning.

It should be understood that the foregoing relates to only a preferred embodiment of the invention, and that it is intended to cover all changes and modifications of the example of the invention herein chosen for the purposes of the disclosure, which do not constitute departures from the spirit and scope of the invention.

The invention claimed is:

1. A control handle controlling the suction to a surgical aspirator, comprising
  - a tubular, rigid body having an axial passage therethrough, said body having an external circumferential groove with a plurality of circumferentially spaced radial holes in said groove extending into said passage for providing lateral

communication between said passage and the exterior of said body,
an elastic ring seated in said groove and manually displaceable at least in part axially of said body for adjustably clearing said holes to control the magnitude of suction in said passage,
one end portion of said body being shaped to engage an end of an instrument for applying suction to an organ of a patient, and
an opposite other end portion of said body being arranged to engage a flexible suction pipe for applying suction to said instrument via said tubular body, whereby partially displacing said elastic ring from said groove will decrease the amount of suction to said instrument and complete displacement of said ring from said groove will remove all suction from said instrument.

2. A control handle as recited in claim 1, wherein said groove has annular shoulders formed at outer edges of said groove for movably seating said ring, the external diameter of said ring being larger than the diameter of said body at said groove and extending radially to facilitate manipulation of said ring by the fingers of one hand grasping said body.

3. A control handle as recited in claim 2 further comprising a nipple having a cylindrical end portion for engaging said other end portion of said body, said cylindrical end portion of said nipple having another external circumferential groove formed therein, and a compressible sealing ring seated in said other groove for sealing said cylindrical end portion of said nipple to said other end portion of said tubular body.

4. A control handle as recited in claim 3, wherein said nipple is formed with a plurality of conical elements extending axially of said nipple for gripping said suction pipe.

5. A control handle as recited in claim 1, wherein said tubular body is formed of a dimensionally stable, sterilizable material.

6. A control handle as recited in claim 1, wherein said passage at said one end portion of said tubular body is conical and flares outwardly for detachably engaging the end of said instrument.

7. A control handle as recited in claim 6, wherein said body has portions intermediate its ends which are respectively cylindrical and conical to facilitate grasping said body while manipulating said ring.

8. A control handle as recited in claim 4, wherein said other end portion of said tubular body is cylindrical for receiving both said cylindrical end portion of said nipple and the free end of said suction pipe.
